DESCRIPTION

FIG. 1 is a front left perspective view of a body mass index meter with detachable bin, showing the new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a back left perspective view thereof; and,

FIG. 9 is a back left perspective view of the new design with the detachable bin shown detached.

The elements shown in broken lines form no part of the claimed design.
